TRUCK DUMPING MECHANISM

Charles R. Golay, Cambridge City, Ind.

Application February 13, 1948, Serial No. 8,167

7 Claims. (Cl. 298—22)

1

This invention relates to a novel and improved elevating hoist for vehicle dumping bodies of which the following is a specification.

The primary object of this invention resides in the provision of an elevating hoist which combines the straight push principle of a hydraulic ram with a fixed arm to achieve a greater dumping angle than has been heretofore attained in such hoists. For the most part the elevating hoists now in use depend entirely on the stroke of a hydraulic ram for their elevation whereas my hoist uses, together with the ram extension, the length of the ram cylinder as an elevating medium.

Another object of this invention lies in the provision of a fixed arm hoist as set forth which, rather than being placed conventionally to act on the rear of the body where the bed lifts heaviest, may be turned around to act beneath the lighter, more easily lifted, forward end of the bed, and to gain the additional benefit of a greater dumping angle.

Still another object of this invention is the provision of an elevating hoist which is a small and compact unit folding into a minimum of space beneath the body, and one which is provided with body and frame supporting members adjustable to various dimensioned frames and bodies.

Still a further and important object of this invention lies in the provision of a dumping body hoist of the character set forth which is highly durable, extremely simple of construction, and therefore inexpensive of manufacture and installation.

Still further improvements and advantages of this invention will readily appear to those skilled in the art when the following description is read in the light of the accompanying drawings.

In the drawings:

Fig. 1 is a perspective view of that portion of the hoist mechanism attached to and supported by the vehicle body.

Fig. 2 is a perspective view of that portion of the hoist attached to and supported by the vehicle frame.

Fig. 3 is a view in side elevation of the portions illustrated in Figs. 1 and 2 in the cooperative positions they assume when the body is elevated, with an intermediate elevated position being shown in dotted line.

Fig. 4 is a view in perspective of a modification of the hoist in an intermediate elevated position, the parts being shown in full line, with a position of greater elevation being shown in dotted line.

2

Referring now to the accompanying drawings which are illustrative of the preferred embodiments of my invention and in which like characters indicate similar parts throughout, A designates the conventional spaced girder frame, and B the body sills, of a common type dumping vehicle in which the body sill is supported on the frame and is pivotally secured transverse the rear end thereof thereby permitting the tilted elevation of the forward end of the sill above the frame.

In order to raise and lower the dumping body relative to the frame an elevating hoist is provided to act cooperatively between the body and the frame. This hoist is automatically, selectively operated through the medium of a hydraulic ram cylinder 1 in which the ram piston 2 is selectively extended or retracted by the operation of a pump or the like carried, usually, in the vehicle cab and interconnected with the ram cylinder by a flexible tubing 3, or the like.

In the present embodiment, illustrated in the drawings, an S beam 4 is secured horizontally transverse the frame and is provided intermediate its length, on its forward face with a pair of horizontally spaced ears 5.

The base end of the hydraulic cylinder 1 is suitably pivoted on a pin 6 which in turn is horizontally supported between the ears 5.

A pair of elongated arms 7 are rigidly interconnected in parallel spaced relationship by joiner plates 8, disposed intermediate their length, and a pair of tubular casings 11 which traverse their remote ends. These arms 7 are disposed longitudinally with and intermediate the sides of the frame A where they are mounted for vertical pivotaction on a pin 9 which extends through one of the tubular casings 11 to be secured at each end thereof to transversely opposed points on the frame A. The pin 9 is secured transverse the frame A at such a distance rearward from the beam 4 so as to dispose the casing 11, which traverses the now free ends of the arms 7, directly above the free end of the ram cylinder 1 when both the cylinder and the arms are substantially horizontally disposed.

The extensible end of the ram piston 2 is pivotally secured on the tubular casing 11 traversing the forwardly disposed free ends of the arms 7, and a pin 10 is revolvably inserted through the casing 11 to project for a spaced distance through and beyond the outer faces of the arms 7. A pair of circular rollers 12, composed of a suitable durable material, are secured one to each of the end portions of the pin 10 where they project beyond the sides of the arms 7.

The foregoing completes the detailed description of the frame supported portion of the hoist assembly and the following is directed to the co-operative portion of the hoist supported by the body of the vehicle.

A pair of cross beams 20, provided with extensions 20a telescopically supported one in each of the ends thereof, are supported transverse the underside of the body in longitudinally spaced relationship by means of L-shaped sill attaching plates 21 carried one by each of the extensions 20a. These cross beams 20 are so secured beneath the body in predetermined spaced relationship that the forwardmost beam will be disposed immediately forward of the vertical plane of the rollers 12 when all parts are in a substantially horizontal position.

A pair of spaced, parallel, inverted L girders 22 are longitudinally disposed beneath the body rigidly interconnecting the two cross beams 20.

A pair of guide tracks for the rollers 12 are formed by the rigid attachment of a pair of vertically spaced, elongated plates 23 and 24 longitudinally beneath each of the inverted L girders 22. These track forming plates 23 and 24 extend longitudinally parallel with, and beneath, the L girders 22 from abutting positions with the forward cross beam 20 to a point substantially two-thirds of the length of the girders 22, where the reputed remaining third portion of the plates is depressed at a predetermined angle from the horizontal to terminate at points beneath the horizontal plane of the body sill.

In assembling the hoist, the rollers 12 are admitted one to each of the guide tracks formed by the spaced pairs of plates 23 and 24 and the cross beams 20 are then secured to the sill members, in the manner described, and in a relative position longitudinal of the body, as described, so as to dispose the rollers 12 at the foremost ends of the tracks against the forward cross beam 20 when the body is in a normal lowered, horizontal position on the frame.

In the elevating operation of the disclosed hoist the ram cylinder is charged to cause the extension of the ram piston 2 which, being pivotally secured to the fixed arms 7, will move with the arms and the cylinder through an increasing vertical arc from the horizontal.

The rollers 12, carried by the arms 7 in the body supported guide tracks, will bear upwardly against the track top with an increase in elevation of the ram and cylinder causing a tilting force to be exerted beneath the body above the frame.

As the frame supported ram assembly continues upwardly in its arc the rollers 12 will move rearwardly in the now inclining track causing a continual increase in the body elevation proportional with the elevation of the ram assembly. When the rollers enter the angular portion of the guide track the body elevation will increase to a greater proportion relative to the ram assembly elevation until the rollers reach the track end at which point the body will be at its maximum angle of elevation.

It can be readily seen from the stepped positions of the assembly illustrated in Fig. 3 that the length of the ram cylinder is applied to the elevation action as an elevating medium thus permitting the attainment of a body elevation angle greater than has been heretofore achieved by elevating hoists used for the purpose specified.

The lowering operation of the body is converse

to the raising operation described, as will be readily apparent.

In the hoist modification, as illustrated in Fig. 4, the ram cylinder 1 and the arms 7 are secured to and supported by the frame in the same manner as previously illustrated and described.

However, replacing the roller 12 on the pin 10, which traverses the now rearward ends of the arms 7, are a pair of short link bars 50 which are each pivotally supported at one of their ends on the opposed, extended ends of the pin 10 to be normally suspended vertically therefrom.

A shaft 51 is rigidly, horizontally, supported between the link bars 50 intermediate their length, and the outer extensible end of the ram piston is pivotally secured on this shaft intermediate the ends thereof.

The lower, extreme ends of the link bars 50 are rigidly interconnected by a second pintle 52 to which one pair of ends of a second pair of link bars 53 are pivotally secured in spaced apart relationship. The second pair of ends of the spaced link bars 53 are revolvably secured on an elongated shaft 54 which is rigidly, horizontally supported longitudinally beneath a cross girder 55, which in turn is secured transverse the underside of the vehicle body.

The action of this modified hoist mechanism operates on the same principle as the preferred embodiment in that it utilizes a fixed arm to bring the length of the ram cylinder into play as an additional elevating member. This form also utilizes a linkage arrangement which increases the angle of elevation attainable over that made possible by the previously described embodiment.

In this modified form the link bars 50 and 53 are so arranged in the assembly as to increase the angle of elevation over the preferred embodiment in that they form the two sides of an obtuse triangle between the fixed arms and the body of which the direct linkage between these elements, as in the preferred embodiment, constitutes the hypotenuse. Thus from common mathematical knowledge it may be readily understood that when these two link bars, forming the sides of the obtuse triangle, are brought into alignment and applied as a single lifting medium they are of a greater linear magnitude than would be a straight interconnection which would constitute the hypotenuse of this triangle.

The dotted line, intermediate lift position of the hoist illustrated as a part of Fig. 4 will clarify an understanding of the lifting action of this modified embodiment.

From the foregoing description and explanation it is seen that an improved elevation hoist for any type of dumping body vehicle is provided which is adjustable to dumping vehicles of various sizes and constructions and a hoist of improved operation functioning to attain an improved result.

I wish it understood that I contemplate any changes and modifications which fall within the scope of the appended claims in which I desire to claim:

What I claim is:

1. An elevating hoist for vehicle dumping bodies comprising, in combination, a vehicle frame, a dumping body pivoted on the frame transverse one end thereof, a pin supported transverse the frame, a reciprocal element pivoted on the pin, a second pin supported transverse the frame, at a spaced distance from the first named pin, an arm pivoted at one end on said second

pin, the free ends of the reciprocal element and the arm revolvably secured on a common pivot, rollers revolvably supported by the free end of the arm in transverse spaced relationship, a guide track for said rollers supported longitudinally beneath the body, said rollers movably confined within the limits of said guide track, and means for reciprocating the reciprocal element.

2. An elevating hoist for vehicle dumping bodies comprising, in combination, a vehicle frame, a dumping body pivoted on the frame transverse the rear end thereof, a pin supported transverse and intermediate the length of the frame, a hydraulic ram cylinder provided with an extensible ram piston, the base of said cylinder pivoted on said pin, a pair of rigidly interconnected parallel arms, a pin revolvably supported transverse one pair of ends of said arms, said pin being rigidly secured transverse the frame rearwardly from said ram supporting pin, a third pin traversing the second pair of ends of said parallel arms, the ram of the ram cylinder revolvably secured on said last named pin, circular rollers revolvably mounted one on each remote end of said last named pin, parallel spaced guide tracks supported longitudinally beneath the body in which said rollers are movably confined, and means for charging the hydraulic ram for the purpose described.

3. A structure as defined in claim 2 wherein, an S beam is rigidly secured transverse and intermediate the length of the frame, a pair of horizontally spaced ears are rigidly secured to the rearward face of said S beam, and said cylinder supporting pin being horizontally supported by and between said ears.

4. A structure as defined in claim 2 wherein, a pair of hollow beams provided with telescopically projected extensions are secured transverse the underside of the vehicle body by means of sill attaching plates carried one by each of said extensions, a pair of spaced parallel girders rigidly interconnect said hollow beams, a pair of elongated vertically spaced plates are secured longitudinally beneath each of said girders in abutment with the forward cross beam, a predetermined portion of these plates adjacent the rear end thereof being angularly depressed from the horizontal, said pairs of plates forming a guide track for the arm supported rollers substantially as and for the purpose described.

5. An elevating hoist for vehicle dumping bodies comprising, in combination, a vehicle frame, a dumping body pivoted on the frame transverse the rear end thereof, a reciprocal element pivoted on the frame, an arm pivoted on the frame at a spaced distance from the reciprocal element, a link bar having one end pivoted to that end of the arm remote to the frame, that end of the reciprocal element remote to the frame being pivoted on said link bar intermediate the length thereof, a second link bar pivoted at its

remote ends to the dumping body and that end of the first named link bar remote to the arm respectively, and means for reciprocating the reciprocal element.

5 6. An elevating hoist for vehicle dumping bodies comprising, in combination, a vehicle frame, a dumping body pivoted on the frame transverse the rear end thereof, a pin supported transverse and intermediate the length of the frame, a hydraulic ram cylinder and ram piston, the base end of said cylinder pivoted on said pin, a pair of rigidly interconnected parallel arms, a second pin rigidly secured transverse the frame rearward of said ram supporting pin, one pair 10 of said arms being pivotally supported on said second pin, a third pin traversing the second pair of ends of said parallel arms, a pair of link bars revolvably suspended by one pair of ends from said last named pin, a shaft interconnecting said 15 links intermediate their length, the outer end of the ram revolvably supported on said shaft, a second shaft interconnecting the second remote ends of the links, a second pair of spaced link bars revolvably connected at their remote ends to 20 said last named shaft and a third shaft rigidly supported transverse the underside of the body respectively, and means for charging said hydraulic ram substantially as and for the purpose described.

30 7. An elevating hoist for vehicle dump bodies comprising in combination, a horizontally disposed elongated vehicle frame, a dumping body horizontally pivoted on the frame adjacent the rear end thereof, a reciprocably extensible element having an end horizontally pivoted on the frame at a point forward of and remote to the pivotal connection of the body to the frame, an arm having an end horizontally pivotally connected to the frame at a point intermediate the 35 pivotal connection of the body and the reciprocable element to the frame, means operatively and pivotally interconnecting the free ends of the reciprocable element and said arm, means operatively linking the interconnected reciprocable 40 element and arm with the body, and means for reciprocating and extending the reciprocable element.
